UNITED STATES PATENT OFFICE

113,361

DESIGN FOR A PHOTOGRAPHIC ENLARGER

John Warren Gillon, Rochester, N. Y., assignor to
Eastman Kodak Company, Rochester, N. Y., a
corporation of New Jersey

Application October 21, 1938, Serial No. 80,594

Term of patent 14 years

To all whom it may concern:

Be it known that I, John Warren Gillon, a citizen of the United States, residing at Rochester, in the county of Monroe and State of New York, have invented a new, original, and ornamental Design for Photographic Enlargers, of which the following is a specification, reference being had to the accompanying drawing, forming part thereof.

In the drawing:

Fig. 1 is a perspective view from the front right hand corner of a photographic enlarger embodying my new design.

Fig. 2 is a perspective view from the front left hand corner of said photographic enlarger also showing my new design.

The mounting base for the photographic enlarger is shown in fragmentary condition in both views for convenience of illustration, the remainder being merely an extension of the part herein disclosed.

I claim:

The ornamental design for a photographic enlarger, as shown and described.

JOHN WARREN GILLON.
